PUMP

Charles I. MacNeil, Glen Ridge, and Henry C. Nette, Rutherford, N. J., assignors to Bendix Aviation Corporation, South Bend, Ind., a corporation of Delaware

Application January 2, 1940, Serial No. 312,166

6 Claims. (Cl. 103—126)

This invention relates to pumps, and particularly to pumps for use in systems wherein a reversal of the direction of fluid flow is occasionally desired, thereby necessitating a reversal of the direction of rotation of the pump.

It is common practice in the manufacturer's design of many types of pumps to vent the oil seal chamber where the shaft emerges from the pump housing and frequently to vent the bearing, to the intake or suction side of the pump. The reason for this practice is to relieve the oil seal and those surfaces of the pump surrounding the bearings, of the necessity of restraining high pressure.

A common practice of pump manufacturers and designers to obtain this result, is to design one housing of the pump so that it may be reversible by removing the housing and rotating it 180°, thereby changing the location of the oil passages inside the pump in respect to the pressure passages in such a manner that the above mentioned oil chambers and bearing cavities are vented to the intake side of the pump.

In view of the desirability that pumps be so manufactured that the necessity of disassembling the pumps in order to obtain the desired results be eliminated, it has been proposed to achieve the desired results by a system of passages and plugs which would be interchanged by a mechanic when changing the pump from one rotation to the other.

By the present invention there is provided a valve arrangement which automatically transfers the vent passages to the intake side of the pump regardless of rotation. While it is possible that other procedures may have been adopted by others this is to the best of our knowledge a new and novel way of achieving the stated result, namely, the assurance of suitable venting action regardless of direction, and without necessity of manual intervention.

Other objects and features of the invention will become apparent from inspection of the following specification when read with reference to the accompanying drawing wherein is illustrated the preferred embodiment of the invention. It is to be expressly understood, however, that the drawing are for the purpose of illustration only, and are not designed as a definition of the limits of the invention, reference being had to the appended claims for this purpose.

In the drawing:

Fig. 1 is a longitudinal sectional view of a device embodying the invention;

Fig. 2 is a second longitudinal sectional view

but with the plane of section at right angles to that of Fig. 1;

Fig. 3 is a transverse sectional view along the line 3—3 of Fig. 1; and

Fig. 4 is a transverse sectional view along the line 4—4 of Fig. 2.

The pump is shown in the drawing as embodied in a housing having two main sections 11 and 12 abutting the opposite surfaces of an intermediate plate 13, the three elements 11, 12, and 13 being retained in assembled relationship by suitable screw bolts 14 and additional retaining screws or bolts 16 spaced angularly from the bolts 14 as indicated. The section 11 includes a flanged portion 17 having one or more openings through which anchoring means may pass for adjustment of the pump to a suitable support, not shown, and in position to receive rotation from a drive shaft 19 having splines or teeth 21 for engagement with the driving element of a prime mover, not shown. The drive member 19 has a socketed portion 23 in which are radially disposed pins 24 serving to transmit the drive to the pump shaft 26 with which is integrated the pump rotor 27 herein shown in the form of a gear adapted to mesh with a corresponding gear 28 (Fig. 2), the latter having cylindrical extensions 31 and 32 integral therewith and journaled in the bearing elements 36 and 37, respectively, of the pump. When the drive shaft is rotating in a clockwise direction as viewed in Fig. 3 the gear elements 27 and 28 cooperate to pump fluid entering chamber 41 and deliver it to the discharge conduit by way of the outlet or pressure chamber 42 while a reversal in the direction of rotation causes chamber 42 to become the suction side and 41 the pressure or outlet chamber. The novel means whereby the oil seal containing chamber 51 (Fig. 1) is automatically vented to the suction side of the pump regardless of the direction of rotation—that is, regardless of whether the side 41 or the side 42 is co-temporaneously serving as the suction or intake side of the pump—is shown in Fig. 4 as including a cylindrical slide valve 52 operating in an obliquely disposed cylindrical bore 54 formed in the bearing element 37, the valve element 52 having circumferential grooves 67 and 68 which—in the position of the valve indicated in Fig. 4—are in communication with longitudinally extending passages 68 and 69, respectively, the former of which is open to the chamber 42 and the latter to the chamber 41. In this position of valve the two ports 71 and 72 (shown as extending vertically in Fig. 4, but actually running diagonally from the chambers at the ends of the rotor bear-

ings 30 and 32, respectively) are in communication with the single circumferential groove at 66 and are therefore in position such that the oil sealing chamber 51 as well as the bearing cavities 83 and 84 are vented to the intake chamber 41 (this being the intake chamber in the direction of rotation in which the valve 52 occupies the position shown in Fig. 4), the path of communication from chamber 51 being by way of radial passage 81 (Fig. 1) the interior 82 of the rotor bearing element 30, the end chamber 83, the port 71, the circumferential groove 66, and the longitudinal passage 69. This condition occurs until the direction of rotation is reversed and there is a consequent reversal of the pressure conditions in the chambers 41 and 42—that is, the chamber 41 now becomes the pressure or outlet chamber and the chamber 42, the suction or intake chamber. When this reversal occurs the resulting pressure change is effective upon the end surfaces of the valve 52 to shift the latter in its cylinder 54 from the position indicated in Fig. 4 to the opposite extreme position whereupon the circumferential groove 67 now comes into communication with the port 71 thereby establishing a pressure relieving path from the oil seal chamber 51 to the chamber 42 which (rather than the chamber 41) is now the intake or suction side of the pump; the new path from the chamber 51 being by way of passages 81, 82, 83, 71, 67, and 68 to the chamber 42.

There is thus provided an automatically acting oil seal pressure relieving means functioning to prevent the development of unduly high pressure in the sealing chamber 51 regardless of the direction of rotation of the pump.

What I claim is:

1. In a pump having a drive shaft and a pair of chambers one of which acts as the suction chamber during rotation of the drive shaft in one direction and as the pressure or outlet chamber during rotation of the drive shaft in the opposite direction, an oil seal containing chamber surrounding the pump rotor drive shaft, and means for automatically establishing and maintaining communication between said oil seal containing chamber and said first-named chamber during rotation of the drive shaft in one direction, said means acting automatically to interrupt said communication in response to reversal in the direction of rotation of the drive shaft.

2. In a pump having a drive shaft and a pair of chambers one of which acts as the suction chamber during rotation of the drive shaft in one direction and as the pressure or outlet chamber during rotation of the drive shaft in the opposite direction, bearing cavities adjacent the pump bearings, and means for automatically establishing and maintaining communication between said bearing cavities and said first-named chamber during rotation of the drive shaft in one direction, said means acting automatically to interrupt said communication in response to reversal in the direction of rotation of the drive shaft.

3. In a pump having a drive shaft and a pair of chambers one of which acts as the suction chamber during rotation of the drive shaft in one direction and as the pressure or outlet chamber during rotation in the opposite direction, a second shaft parallel to said drive shaft, an oil seal containing chamber, and means interposed between said parallel shafts for automatically establishing and maintaining communication between said oil seal containing chamber and said first-named chamber during rotation of said drive shaft in one direction, said means acting automatically to interrupt said communication in response to reversal in the direction of rotation of said drive shaft.

4. In a pump having a pair of interengaging gears, each with extending hollow hubs forming bearing cavities, means interposed between said hollow hubs to control the venting of said bearing cavities, said means including a valve movable from one extreme position to the other, and means operative in response to reversal of the direction of rotation of said gears to vary the pressure acting upon said valve and thereby shift said valve in its relationship to said cavities, to direct fluid flow from said cavities to one side of the pump for one direction of rotation, and to the other side of the pump during rotation in the opposite direction.

5. In a pump having a casing including a cover plate on one side and a drive-shaft-receiving section on the other, said drive-shaft-receiving section including a sealing chamber having sealing means therein, conduits leading from said casing, one of said conduits being the inlet during clockwise rotation of said drive-shaft, the other being the inlet during counterclockwise rotation of said drive-shaft, and means operative independently of said cover plate for causing a discharge of fluid from said sealing chamber to the particular conduit constituting, at any given time, the inlet conduit.

6. In a hydraulic pump, a housing formed with a pump chamber having fluid openings communicating respectively with said chamber at diametrically opposite sides, each of said openings being adapted to function as a pump inlet or outlet, meshing pump gears, rotatably disposed in said chamber and adapted for rotation in either a forward or reverse direction, drive shaft means for said gears including a sealing chamber having sealing means therein, a bore in said housing, a conduit connecting said sealing chamber and said bore, a passageway leading from each fluid opening to a respective end of said bore and a fluid pressure actuated member slidably disposed in said bore and selectively operable for causing a discharge of fluid from said sealing chamber to the particular fluid opening constituting at any given time the pump inlet opening regardless of the direction of rotation of said gears.
